UNITED STATES PATENT OFFICE.

GEORGE FRANCIS DOWNS, OF BUFFALO, NEW YORK.

APPARATUS FOR COATING METAL-INGOT MOLDS.

1,243,718.

Specification of Letters Patent.

Patented Oct. 23, 1917.

Original application filed December 16, 1916, Serial No. 137,417. Divided and this application filed July 7, 1917. Serial No. 179,123.

To all whom it may concern:

Be it known that I, GEORGE F. DOWNS, a citizen of the United States, and a resident of Buffalo, in the county of Erie and State of New York, have invented certain new and useful Improvements in Apparatus for Coating Metal-Ingot Molds; and I do hereby declare that the following is a full, clear, and exact description thereof, reference being had to the accompanying drawings, and to the letters of reference marked thereon, which form a part of this specification.

This invention relates to an improved apparatus for coating the inside surface of steel-ingot-casting molds and consists of the matters hereinafter described and more particularly pointed out in the appended claims.

The present application is a divisional application, the matter herein having been first presented in an application for Letters Patent filed by myself on December 16, 1916, and bearing Serial Number 137,417. The object and the advantages of the present invention will appear as I proceed with my specification.

A factor of primary importance in steel making is the preparation of the steel ingot itself, and particularly as to the formation and condition of its outer surface. After the molten metal has been poured into the mold and when it is being allowed to cool, it is of prime necessity that the outer surface of the ingot shall not stick to the mold during the time it is cooling. During this stage of forming the ingot, its outer skin is quite tender and cracks are likely to form unless a perfectly free contraction of the ingot is possible, without the sticking or adhering of the outer surface of the ingot to the inner surface of the mold. These cracks in the surface of the ingot, as is well known, result in seams and surface defects that are produced when rolling the ingot.

It has been customary heretofore to coat the inner surface of the mold to insulate the inner mold surface and to prevent adhesion of the ingot to said surface during the cooling period. To this end, various washes, consisting of mixtures of water with clay, ganister, lime or graphite, in certain proportions to give the proper fluid consistency, have been used. These washes have

been applied in various ways, as for example, by spraying, by means of brushes or swabs, and by splashing,—the end and aim in each case being to cover as much of the inside surface of the mold as possible. None of the above methods, however, have been capable of depositing the insulating, non-adherent wash in a uniform layer or film upon the inside surface of the mold.

The object of my improved apparatus is to apply an insulating wash of the kind described in a uniform, even, smooth layer or film, completely covering the entire inner surface of the mold, and filling in and smoothing over all inequalities and depressions therein.

My improved apparatus includes a tank or other suitable reservoir in which I provide a wash consisting of water and of clay, ganister, lime, or graphite, in the necessary proportions to produce a mixture of such fluid consistency that it will stick or adhere to the surface of the mold when applied thereto. The mold is partly or wholly dipped into or submerged in the fluid mixture in said tank so as to bring all of the inner surface of the mold into contact with the mixture or wash.

The mold is then withdrawn from the fluid mixture and the outside surface of the mold is washed or cleaned by sprays of water or otherwise, to remove the insulating wash or mixture from said outer surface. The mold is then in readiness for use in pouring the molten metal to form the ingot.

In the drawings:

Figure 1 is a diagrammatic view, representing in vertical elevation and partially in vertical section, my improved apparatus for coating the inner surface of steel-ingot-casting molds.

Fig. 2 is a view showing the dipping tank forming a part of my improved apparatus, in vertical section, the plane of the section being at right angles to that of Fig. 1, with the mold car placed adjacent thereto.

Fig. 3 is a top plan view of the dipping tank.

Referring now to that embodiment of my improved apparatus, as illustrated in the accompanying drawings:—10, 10 indicate the upright beams of a traveling crane

structure; 11, 11, the upright posts; 12, 12, I-beam stringers, and 13, 13, the rails supported thereon, and providing tracks for the wheels 14, 14, of a traveling crane 15. 15 The upright beams 10, 10, are connected together at their top by suitable tie members 16, and the I-beams 12 are braced from said upright members by means of plates 17, 17; 18 indicates a transverse shaft mounted on 19 the traveling crane 15 and adapted through suitable gearing 19, 19, to drive the wheels 14, 14, along the tracks 13, 13; 20 indicates the motor for driving the shaft, and 21, the operator's cab in which is provided a suitable mechanism for controlling the motor. 22 indicates a transversely moving carriage mounted on rails 23 on the top of the traveling crane 15. A differential drum 24 is mounted on this carriage and is driven by 25 gearing 25, actuated in a familiar manner by a motor 26 mounted on the carriage, and arranged for control by the operator in the cab 21.

27 indicates an open vessel or tank set in 25 the ground or floor 28, upon which the traveling crane structure is erected. This tank consists, as shown, of a substantially rectangular box made of concrete or other suitable material, and preferably provided 30 with a metallic sheet lining 29. Preferably, said tank projects above the floor or ground level 28, as shown; a trackway 30 is arranged alongside the tank 27 for a mold car 31. The tank 27 constitutes the dipping 35 tank and contains the mixture of insulating wash or fluid, consisting of water and of the several substances, clay, ganister, lime or graphite, as heretofore described.

The dipping tank is provided with means 40 for agitating the fluid mixture contained therein. As shown, this means consists of an air blast pipe 32 which is located at one side of the tank and which depends into the tank to a point near the bottom thereof. 45 There is also provided means for heating the dipping mixture, which, as shown, consists of a steam pipe 33 leading from any convenient source of steam supply (not shown) and depending into the tank.

50 About the top of the dipping tank, there is placed a perforated pipe 34 built in the form of a hollow rectangle, with the perforations directed toward the interior of the tank, and connected to a supply pipe 35. 55 Said pipe 35 has a hand valve 36 adapted to admit water under pressure into the pipe 34, from which it will be discharged through the perforations therein into the space defined by the four upright walls of the tank.

60 In the bottom of the tank is placed a basket 37 which is preferably in the form of a shallow, rectangular, open box having a perforated bottom wall 38. This basket is provided with chains 39 connected to its 65 four corners,—there being one chain at each

end of the basket. Said chains are normally looped upon hooks 40 fixed in the end walls of the tank 27 near its top. These chains may be engaged by the grapple of the traveling crane 15 to withdraw the basket 70 from the tank, as will be presently described.

45 indicates the ingot molds. Said molds (one or more at a time,—two, as shown) are dipped in the fluid mixture in the tank by 75 means of a grapple 46 attached to the blocks 47 connected in the usual manner by ropes or chains 48, to the differential drum 24 of the traveling crane. The grapple is operated by the usual trip rope 49 in such a 80 manner as to connect with or to be detached from the usual ears 45^a on the molds 45.

The operation of my improved apparatus is as follows. The dipping tank is filled with one of the fluid insulating mixtures 85 heretofore described. Steam is admitted through the pipe 33 in order to heat the mixture to a point somewhat below that of boiling water. At the same time, in order to maintain a thorough mixture of the wash, 90 in which the solid material is merely suspended and not dissolved, air under pressure is admitted through the air pipe, and this air, escaping under the surface of the fluid in the tank, will agitate the mixture, 95 maintain the solid material in suspension and produce and maintain a constant, uniform mixture.

A number of molds 45 are brought on the mold car 31 into a position adjacent to the 100 tank 27. The traveling crane and the carriage 22 thereon, are brought in a familiar manner above the molds on the mold car, and the block and grapple 47, 46, are operated to lift the molds from the mold car 105 and to lower them into the tank 27 until they are completely immersed in the insulating fluid mixture therein. The molds are allowed to remain therein until a film or coating of the insulating mixture has adhered to the surface of the molds. The differential drum of the crane is then operated to raise the molds from the dipping tank. As a mold is raised, the valve 36 is 110 opened to supply water through the pipe 115 34, and this water is discharged through the perforations of said pipe against the mold, so as to clean and remove the wash or insulating mixture from its outer surface. The mixture, after it is washed off the outer 120 surface of the mold, drips back into the tank together with the wash water. The dipped molds are then returned to the mold car, and another mold or set of molds is brought above the tank and dipped into it, 125 as before described. After all the molds have been thus treated, they are taken away and the molten steel is poured into them in the usual manner.

The fluid mixture in the dipping tank is 130

kept at a temperature between 100° and 200° F. The advantage of maintaining the fluid mixture at this temperature, is that cold molds will be warmed up and raised to a 5 temperature above that of the atmosphere during the dipping thereof, so that they will be in a more desirable condition as to temperature to receive the molten steel poured into them. Again, by maintaining the 10 temperature of the dipping mixture at the degree described, the chilling of hot molds, when dipped into the mixture, is prevented.

The spray water pipe 34 not only acts to clean the outside surface of the mold and 15 remove the insulating mixture therefrom, but it also, being cold and dripping into the dipping tanks, keeps down the temperature of the dipping mixture below the boiling point of water, when the temperature 20 of the mold that is being treated exceeds that temperature. The addition of water in this washing process, to the fluid mixture in the dipping tank, is compensated for by the evaporation that takes place, due to the 25 temperature of the dipping mixture.

By dipping the molds as herein described, the interior surface of the mold is provided with a smooth, uniform layer of insulating material, and this layer or coating is applied to every part of the said interior surface. Said uniform coating not only protects the mold and prolongs its life, but it obviates surface flaws in the ingot and permits free stripping of the steel from the 30 inner surface of the mold as the ingot contracts. In addition, when the steel is poured, the small particles of molten metal that are splashed or thrown up against the mold surface as the molten steel rises therein, do not 35 stick to the surface of the mold, but drop back into the molten mass.

Any sediment or particles of foreign substance that fall into the dipping tank, will collect in the basket 37, which may be withdrawn at intervals to remove the same.

In describing my improved apparatus, I have stated that the mold is completely submerged in the fluid mixture contained in the dipping tank. It will be understood, of course, that complete submersion is not necessary, it being simply required to immerse the mold to such an extent that the fluid, insulating mixture will be brought into contact with the entire interior surface of the 50 mold, or with so much of said surface as will be brought into contact with the molten metal when the ingot is poured.

I claim as my invention:

1. An apparatus for use in applying a 60 uniform layer of insulating material upon the inner surface of a mold for metal ingots, comprising an open vessel adapted to contain a mixture of the insulating material, means associated with said vessel for dipping molds thereinto and for removing 65

the molds therefrom, means for agitating the mixture in said vessel, means for heating said mixture, and means for discharging a wash fluid against the outer surface of the mold as the same is withdrawn from 70 said vessel.

2. An apparatus for use in applying a uniform layer of insulating material upon the inner surface of a mold for metal ingots, comprising an open vessel, a blast pipe depending into said vessel, a steam pipe depending into said vessel, a spray pipe surrounding the top of said vessel, a hand valve for controlling the supply of water to said spray pipe, and means associated with said 80 vessel for dipping into and removing molds from said vessel.

3. An apparatus for use in applying a uniform layer of insulating material upon the inner surface of a mold for metal ingots, including an open vessel, a blast pipe depending into said vessel, a steam pipe depending into said vessel, a spray pipe surrounding the top of said vessel, a hand valve for controlling a supply of water to said 85 spray pipe, and a shallow, open basket having a perforated bottom wall resting on the bottom of said vessel and being provided with means for removing it from said vessel. 95

4. An apparatus for use in applying a uniform layer of insulating material upon the inner surface of a steel-ingot-mold, comprising an open vessel having upright side and end walls adapted to contain a mixture 100 of the insulating material, means associated with said vessel for dipping a mold thereinto and for removing it vertically therefrom, means for agitating the mixture in said vessel, means for heating said mixture and 105 means for discharging a wash fluid against the outer surface of the mold as it is withdrawn from said vessel.

5. An apparatus for use in applying a uniform layer of insulating material upon 110 the inner surface of a steel-ingot mold, having a vertically disposed ingot chamber, comprising an open top vessel adapted to contain a mixture of the insulating material, means associated with said vessel for 115 dipping a mold thereinto and for removing it vertically therefrom, and means for discharging a wash fluid against the outer surface of said mold as it is withdrawn from said vessel. 120

6. An apparatus for use in applying a uniform layer of insulating material upon the inner surface of a steel-ingot mold, comprising an open top vessel adapted to contain an insulating mixture, a tramway and 125 car adapted to convey the mold into a position adjacent the vessel, a traveling crane associated with the tramway and vessel, adapted to handle the mold to take it from the tram car and dip it into the vessel, 130

4
means for agitating the mixture in said vessel, means for heating said mixture, and a spraying device located adjacent the top of the vessel adapted to discharge a wash fluid against the outer surface of the mold as it is withdrawn from said vessel.

5
In testimony that I claim the foregoing as

my invention I affix my signature in the presence of two witnesses, this 3rd day of July A. D. 1917.

GEORGE FRANCIS DOWNS.
